UNITED STATES PATENT OFFICE.

EUCLID I. LA CHAPELLE, OF BEVERLY, MASSACHUSETTS, ASSIGNOR TO UNITED SHOE MACHINERY COMPANY, OF PATERSON, NEW JERSEY, A CORPORATION OF NEW JERSEY.

SOLE-LEVELING MACHINE.

1,143,717.

Specification of Letters Patent. Patented June 22, 1915.

Application filed May 21, 1908. Serial No. 434,042.

To all whom it may concern:

Be it known that I, EUCLID I. LA CHAPELLE, citizen of the United States, residing at Beverly, in the county of Essex and State 5 of Massachusetts, have invented certain new and useful Improvements in Sole-Leveling Machines; and I do hereby declare the following to be a full, clear, and exact description of the invention, such as will enable 10 others skilled in the art to which it appertains to make and use the same.

The present invention relates to sole leveling machines intended more particularly for leveling the soles of turned shoes, although 15 various features of the invention may be embodied with advantage in machines intended for use in leveling welt shoes.

In the manufacture of turned shoes, the edge of the sole is bent or molded away from 20 the lip previous to the sewing of the upper to the sole, and after the shoe has been turned and re-lasted this molded edge appears as a well defined ridge extending around the margin of the sole. In leveling 25 turned shoes by hand the operator removes this marginal ridge by subjecting the marginal portion of the sole to an outward rubbing pressure with a rubstick. The final 30 pressing and shaping of the sole is secured by subjecting the sole to a longitudinal rubbing pressure with a rubstick.

It is the object of the present invention to provide a machine by which the sole of the 35 shoe may be subjected to an outward rubbing pressure along its margin, and to a final longitudinally progressive pressure to bring it to its final shape, and by which the leveling operation may thus be quickly performed, and with as good results as are produced 40 by the hand leveling operation when performed by a skilled operator.

In accordance with one feature of the invention, the marginal portion of the sole is progressively acted upon by a leveling device 45 which is forced repeatedly against the sole and is moved laterally outward over the marginal portion while in engagement therewith. The outward rubbing pressure thus produced stretches the marginal portion of 50 the sole outward, thus removing the marginal ridge, and the rapid repetition of this outward stretching pressure gives a permanent set to the molded edge, so that it will not tend to subsequently return to its original 55 distorted shape.

A further feature of the invention contemplates the provision of devices for simultaneously and progressively subjecting the opposite sides of the sole to rapidly repeated outward rubbing pressure. This insures the accurate shaping of the sole, since the lateral strains are balanced, and each side is held from distortion while the other side is being operated upon, and also increases the rapidity with which the leveling 60 of the sole may be completed. In accordance with this feature in its broader aspects, any suitable form and arrangement of devices for subjecting the marginal portions of the sole to repeated compression and outward stretching may be employed. In their preferred form, however, these devices consist of tools arranged to act upon opposite sides of the sole, and so operated that they independently apply pressure to the sole. 65 By thus operating the tools an effective action on each side of the sole is insured, since the pressure applied to the sole by each tool is unaffected by variations in the resistance offered by the sole to the other tool. 70

In leveling turned shoes it is frequently desirable that the center as well as the marginal portions of the sole shall be subjected to repeated compressions while operating on certain parts of the sole, and that the marginal portions only should be subjected to such operation while operating upon other parts of the sole. 75

Another feature of the invention accordingly contemplates the provision of means 80 for repeatedly compressing the center and sides of the sole and for arresting the action of said means upon the center of the sole while continuing the action on the sides. 85

A further feature of the invention contemplates the provision in a machine provided with means for subjecting the sole to repeated compressions, of an additional leveling device for applying a longitudinally progressive pressure to the sole to smooth 90 out and press the sole into final shape. By providing such a leveling device, which acts upon the sole during the action of the compressing devices, the rapidity of the leveling operation is increased, and any irregularities produced by the compressing devices are 100 immediately removed. 105

The leveling device which I prefer to employ for giving the final shape and finish to the sole is a vibrated leveling roll such as is 110

commonly employed in sole leveling machines, and certain features of the invention contemplate the provision of a novel and improved construction and arrangement of the mechanism for varying the lateral inclination of such a roll. In accordance with one of these features, the leveling roll is so mounted that the axis about which it is turned in varying its lateral inclination is shifted laterally toward the side of the sole on which the roll is to operate. This enables the roll to be tipped to operate upon the shank without materially changing the relation between the sole and the bed in which the roll is carried, and is of especial advantage in case other leveling devices are mounted upon the same bed with the roll. In accordance with another of these features, the mechanism for changing the lateral inclination of the roll is constructed to lock the roll against displacement under the pressure exerted thereon by the sole, so that the operating lever is unaffected by the pressure between the roll and sole tending to vary its lateral inclination.

A further feature of the invention contemplates the provision of means for smoothing out the heel and shaping the heel seat of the shoe, the sole of which is being leveled. This means is preferably so constructed and arranged that it will operate upon the heel of the shoe supported on the jack during the forward and return movements of the jack, and will thus smooth out the heel and shape the heel seat during the operation of the leveling devices upon the sole. In its broader aspects this feature of the invention contemplates the employment of any suitable form and arrangement of means for smoothing out the heel and shaping the heel seat, which is constructed and arranged to operate upon the heel of the shoe during the leveling operation. In its preferred form, however, the means for smoothing the heel and shaping the heel seat include certain features of invention which are not limited in their application to constructions in which the heel seat is shaped and the heel smoothed during the leveling operation, but may be embodied in machines which are not provided with means for leveling the sole.

The invention also includes certain further features which will be referred to in connection with the description of the machine in which I have embodied the invention, and will be set forth in the claims.

The various features of the invention will be readily understood from an inspection of the accompanying drawings, in which—

Figure 1 is a side elevation of a leveling machine embodying all the various features of the invention in the forms in which I prefer to employ them; Fig. 2 is a plan view partly in section; Fig. 3 is a section on line $x-x$, Fig. 2; Fig. 4 is a detail view partly in

section, looking from the side opposite to that shown in Fig. 1, and showing the parts in a different position; Fig. 5 is a section on line $z-z$, Fig. 1; Fig. 6 is a section on line $y-y$, Fig. 5; Fig. 7 is a section on line $v-v$, Fig. 3; Fig. 8 is a detail front view of the compressing tools; Fig. 9 is a similar view showing the tools in different position; Fig. 10 is a section on line $u-u$, Fig. 3; Figs. 11 to 17 are detail views showing the operation of the mechanism for starting and stopping the operating mechanism for the compressing tool; Fig. 18 is a section on line $w-w$, Fig. 2; Fig. 19 is a sectional elevation showing a modified form of means for controlling the action of the compressing tools; Fig. 20 is a plan view of the devices shown in Fig. 19; Fig. 21 is an elevation looking toward the right in Fig. 19; Fig. 22 is a transverse sectional view through the side compressing tools; Fig. 23 is a side elevation showing a modified construction in which the jack carries means for smoothing the heel and shaping the heel seat of a shoe supported on the jack; Fig. 24 is a transverse sectional view showing the operation of the smoothing hammers; Fig. 25 is a plan view showing the arrangement of the hammers; and Fig. 26 is a detail view showing the cams for operating the said hammers.

In the machine shown in the drawings the relative movements between the shoe supporting jack and the leveling devices for transferring the point of operation of the leveling devices along the shoe sole are produced by advancing and retracting the jack. The leveling mechanism comprises two compressing tools arranged to operate upon opposite sides of the bottom of the sole, a third compressing tool arranged to operate upon the center portion of the sole, and a leveling roll, the lateral inclination of which may be varied in accordance with the part of the sole being operated upon. The leveling devices are arranged and operated to complete the leveling of the sole during the forward and return movement of the jack. The leveling roll remains in engagement with and operates upon the sole during the entire forward and return movement of the jack. As the jack starts forward, the center and side compressing tools are brought into action, and continue in action until the shank is reached, when the action of the center tool is arrested, the side tools continuing to act through the shank. When the breast of the heel seat is reached by the leveling roll, the motion of the jack is reversed, and at the same time the compressing tools are thrown out of action, so that during the return movement of the jack the sole is acted upon by the leveling roll only. The roll is arranged to act upon the sole during the advance movement of the jack after the sole has been subjected to the action of the com-

pressing tools, and thus during the advance movement of the jack the roll acts to level and give final shape to that portion of the sole which is operated upon by the roll during this movement of the jack. During the forward movement of the jack, the leveling roll, as it reaches the shank of the sole, is tipped so that it will operate upon and finish one side of the shank. On the return movement of the jack, and after the compressing tools have been thrown out of action, the leveling roll is tipped so that it will act on the other side of the shank, and will level and finish this side of the shank during the first part of the return movement of the jack. When the ball line is reached during the return movement of the jack, the leveling roll is tipped to act upon that portion of the fore part which has not been properly leveled during the advance movement of the jack.

The jack upon which the shoe is supported comprises a frame 1 pivotally supported upon a shaft 2, and provided with shoe supporting devices 3 which may be of any suitable construction. The jack frame is connected by means of a link 4 with a crank 5 which is secured to a crank shaft 6. During the operation of the machine the crank shaft 6 is given an oscillatory movement to advance and retreat the shoe supporting jack.

The leveling devices are mounted in a vertically movable bed 7 pivotally mounted and normally supported by a spring 9. The downward movement of the front end of the bed 7 is limited by a stop nut 10 carried by a stop rod 11 and arranged to engage a pin 12 on the rear end of the bed. The bed 7 may be yieldingly forced in a direction to force the leveling devices into engagement with the sole of a shoe carried by the jack by the depression of a treadle 13. The treadle is connected by means of a link 14 with a block 15 which is in turn connected by a rod 16 with the bed 7. A spring (not shown) is interposed between the rod and the block 15 in a well known manner, so that when the treadle 13 is depressed the front end of the bed 7 is forced downward with a pressure dependent upon the tension of the spring within the block 15. The pressure exerted by the spring may be regulated by means of a nut 17 mounted on the upper end of the rod 16, and arranged to engage the bed 7.

The leveling devices carried by the bed 7 consist of two compressing tools 18 and 19 arranged to act upon opposite sides of the sole of a shoe supported on the jack, a third tool 20 arranged to act upon the center portion of the sole, and a leveling roll 21 so mounted in the bed that its lateral inclination may be varied in accordance with the portion of the sole to be acted upon. The tools 18, 19 and 20 are carried in a head 22

mounted to reciprocate vertically in the front end of the bed 7. The center tool 20 is mounted upon the lower end of a rod 23 which extends vertically through the head 22 and is held in normal position in the head 70 by a spring 24. The side tools 18 and 19 are mounted upon the lower ends of two rods 25 and 26 which extend up through the head 22 and are held in normal position in the head 75 by springs 27 and 28. The recess in the head in which the rod 23 for the center tool is mounted is so arranged that the rod 23 is substantially perpendicular to the surface of the sole upon which the center tool acts. The recesses in which the rods 25 and 26 carrying the side tools are mounted, converge laterally toward the sole, as indicated in Figs. 8 and 9. The side tools 18 and 19 are pivotally mounted on the lower ends of the rods 25 and 26, so that they may rock laterally, and automatically conform to the lateral curvature of the sole, and are held in normal position by springs 29. The center tool is pivotally mounted upon the lower end of the rod 23, so that its operating surface 80 85 90 95 100 105 110 115 120 125 130 may conform to the longitudinal curvature of the sole.

During the operation of the compressing tools upon the sole the head 22 is reciprocated through a bell crank lever 30, one arm 95 of which is connected by a link 31 with the head, and the other arm of which is connected by a link 32 and pivotally supported arm 33 with the front end of an eccentric rod 34, the rear end of which embraces an eccentric 35 mounted on the shaft 8. During the downward movement of the tool carrying head 22 the center tool first engages the center portion of the sole, and then during the continued downward movement of the head the spring 24 yields to accommodate the downward movement of the head, and acts to increase the pressure of the tool upon the sole. Immediately after the center tool engages the sole, the two side tools engage the 110 marginal portions of the sole, and then during the continued downward movement of the head 22 the springs 27 and 28 yield to allow the head to move downward with relation to the tools, and act to increase the 115 pressure of the tools upon the sole during the continued downward movement of the head. The downward movement of the head with relation to the tool carrying rods 25 and 26, after the downward movement of the 120 tools has been arrested by their engagement with the sole, moves the tools transversely outward over the margin of the sole, as indicated in Figs. 8 and 9. Thus the tools are actuated to repeatedly apply pressure 125 to the sole substantially perpendicular to the surface being operated upon, and the side tools are moved transversely outward over the margin of the sole while pressed firmly against the sole, the tools rocking on 130

their pivots so that their working surfaces automatically conform to the curvature of the sole at the point of operation. By reason of the laterally outward movement of the 5 side tools as they are repeatedly pressed against the sole, they act to outwardly stretch and compress the marginal portions of the sole, thus bringing the molded edge down into shape and giving it a permanent 10 set. The compressing tools on opposite sides of the sole are moved simultaneously outward in opposite directions, and therefore the lateral strains produced by the action of the tools are balanced, and each side of the 15 sole is held from distortion while the other side is being operated upon. At the same time the center tool is acting upon the center portion of the sole so that the sole is actually shaped and brought into position 20 against the last. The force with which each tool is pressed against the sole is determined by the spring acting upon the rod which carries the tool, and therefore the pressure and rubbing action exerted by each tool is 25 unaffected by the resistance offered by the sole to the other tool or tools.

The leveling roll 21 is arranged back of the leveling tools so that it acts upon the sole immediately after the tools have acted 30 upon it, and applies to the compressed and laterally stretched sole a longitudinally progressive pressure which removes any irregularities formed by the compressing and rubbing tools, and finally shapes and finishes 35 the bottom of the sole. The leveling roll is mounted in a yoke 36 formed on the front end of a shaft 37, which is mounted in a carriage 38, the shaft being so arranged that the lateral inclination of the roll 21 may be 40 varied by turning the shaft in its bearings in the carriage 38. The carriage 38 is mounted to move laterally in guiding ways formed in a cross-bar 39 of the bed 7, and in a transverse bracket 40 secured to the under side of the bed (Figs. 2, 3 and 7). The front end of the carriage 38 is provided with a roll 41 arranged to engage a bearing surface 42 formed on a cross-bar 43 of the bed 7. At its rear end the roll carrying shaft 45 50 37 is provided on opposite sides with recesses 44 which are engaged by arms 45 of a yoke 46 pivoted on a reciprocating slide-bar 47. By this connection between the shaft 37 and the reciprocating bar 47, the shaft 37 and the leveling roll 21 are caused to reciprocate 55 with the bar 47. By reason of this connection, also, the lateral movements of the carriage 38 will cause the shaft 37 to be rocked to tip the roll 21 laterally in one direction 60 or the other, according to the direction in which the shaft is moved from its normal position vertically above the bar 47.

The lateral inclination of the leveling roll 21 is controlled by the operator through an 65 operating lever 48, the rear end of which

is provided with a gear segment 49 engaging a pinion 50 secured to a shaft 51 which is mounted in the bed 7. The shaft 51 carries a spiral gear 52 which engages a rack 53 formed on the carriage 38. When the lever 70 48 is in mid-position, as indicated in Figs. 2 and 3, the shaft 37 carrying the leveling roll 21 is in mid-position vertically over the reciprocating bar 47. If the lever 48 is moved in either direction from the mid- 75 position, the movement imparted to the shaft 51 and spiral gear 52 in one direction or the other, as the case may be, will move the carriage 38 laterally toward one side or the other, thus carrying the pivotal axis about 80 which the roll 21 turns laterally toward one side or the other of the sole, and at the same time turning the shaft 37 about its axis to tip the roll in one direction or the other. By thus shifting the axis about which the roll is 85 tipped in varying its lateral inclination, the working surface of the roll, when the roll is in its different positions, remains in substantially the same vertical relation to the bed 7, so that the relation of the bed to the 90 sole being operated upon is not materially varied in tilting the roll to give it its extreme lateral inclination when acting on the shank. The tilting of the roll does not, therefore, modify the relation of the compressing tools to the sole to such an extent as to interfere with their proper operation upon the sole, as might be the case if the axis about which the roll is tipped were not 95 shifted in varying the lateral inclination of 100 the roll.

The connections between the lever 48 and the leveling roll enable the operator to readily vary the lateral inclination of the roll by manipulation of the lever, and at the 105 same time the roll is locked by the gear 52 and rack 53 against displacement under the pressure exerted thereon by the sole, so that the pressure is not transmitted through the connections to the operating lever. No exertion on the part of the operator, therefore, is required to maintain the leveling roll in the position into which it is moved by manipulating the operating handle. The bar 47 is continuously reciprocated during 115 the operation of the leveling roll upon the sole by the action of an eccentric 54 carried by a continuously running shaft 55, and embraced by an eccentric rod 56, the front end of which is connected with the 120 bar by a link 57.

During its advance movement the jack is advanced intermittently, and the compressing tools are actuated to operate upon the sole during the intervals between the advance movement of the jack. At the end of the advance movement of the jack the mechanism for intermittently advancing the jack and the mechanism for operating the compressing tools are thrown out of operation, 125 130

and the eccentric 35 which actuates the tool-carrying head, is arrested in position to hold the tool-carrying head at the upper end of its stroke, where the tools are held out of engagement with the sole. The mechanism for intermittently advancing the jack consists of a ratchet wheel 58 secured to the crank shaft 6, and arranged to be engaged by an operating pawl 59 and a stop pawl 60 (Figs. 1 and 4.) The operating pawl 59 is reciprocated by means of an eccentric 61 secured to a shaft 62, and embraced by the upper end of the pawl. The shaft 62 is rotated through a shaft 63, the lower end of which is connected with the shaft 62 by gearing 64, and the upper end of which is provided with a beveled gear 65 meshing with a gear 66 which is connected to rotate with the eccentric 35 which operates the compressing tools. The pawls 59 and 60 are normally held out of engagement with the ratchet wheel 58, by means of a guard plate 67 formed on the rear end of a lever 68, which is pivoted at 69 to the frame of the machine. The lever is held normally in position to retain the pawls out of engagement with the ratchet wheel by a spring 70, which forces a pin 71 against the lower side of the lever. The lever is operated to release the pawls so that they will engage and operate upon the teeth of the ratchet wheel through a latch rod 72 provided at its upper end with a shoulder 73 arranged to engage a lateral projection 74 on the lever 68. A spring 75 tends to hold the latch bar in engagement with the lever. The lower end of the latch bar is connected through a spring 76 with a casing 77, the lower end of which is connected by a link 78 with a treadle 79. The treadle 79 is pivotally supported upon and forms a forward extension of the treadle 13. When the jack is to be advanced, the operator depresses the treadle 79 from the dotted line to the full line position, Fig. 1. The first downward movement of the treadle 79 operates through the latch 72 to depress the pawl guard lever 68 and release the pawls, so that they will engage the ratchet wheel, and then continued downward movement of the treadle forces the bed 7 which carries the leveling devices down so that the leveling devices will operate properly upon the sole of the shoe carried by the jack.

At the same time that the jack operating pawls are thus thrown into operation, the mechanism for rotating the eccentric 35, which operates the compressing tools, and for driving the gearing through which the operating pawl 59 is reciprocated, is thrown into action.

The eccentric 35 and the pawl operating gearing is driven through a friction clutch, one member 80 of which is secured to the eccentric, and the other member 81 of which

is secured to the continuously rotating eccentric 54 which vibrates the leveling roll. The eccentric 54 and clutch member 81 are formed on a sleeve 82 which is connected to rotate with and slide on the end of the continuously rotating shaft 55 (Fig. 18.) The sleeve 82 is operated to engage and disengage the clutch formed by the members 80 and 81, by means of a wedge 83 provided with two vertically extending arms having inclined surfaces arranged to engage corresponding surfaces on a wedge block 84 which is mounted to slide on the shaft 55. The wedge block 84 is connected with the clutch sleeve 82 by an arm 85, one end of which is secured to the wedge block, and the other end of which engages an annular groove formed in the sleeve. The clutch operating wedge 83 is forced in a direction to engage the clutch by a spring 87 which forces a pin 88 against the under side of the wedge. The clutch operating wedge is normally held in its lower position so that the clutch members are disengaged. The clutch operating wedge is released so that it is operated by its spring to engage the clutch, and thus throw the operating mechanism for the compressing tools and the intermittent jack operating mechanism into operation when the operator depresses the treadle 79. At the same time the devices which maintain the operating eccentric in normal position with the compressing tools raised, are thrown out of operation. These devices consist of a cam disk 89 connected to rotate with the clutch member 80 and eccentric 35, and a lever 90 provided with a brake shoe 91 arranged to engage the surface of the cam disk.

The means for controlling and operating the clutch operating wedge and the brake lever are shown in Figs. 3 and 10 to 17. The normal position of the parts, when the jack is in its retracted position, and the compressing tools are out of operation, is shown in Fig. 15. As here shown, the brake shoe 91 on the lever 90 is in engagement with a shoulder 92 on the cam disk 89, and the wedge 83 is held in its lower position. The lower end of the wedge 83 is pivotally connected to an arm 93 secured to a shaft 94 (Fig. 10). The shaft 94 also has secured to it a collar 95 which is provided with a lug 96 arranged to be engaged by a spring latch 97 pivoted on the brake lever 90. When the parts are in the position of Fig. 15, the latch 97 is in engagement with the lug 96, and the shaft 94 is held from movement under the influence of the wedge operating spring 88 by the engagement of the brake lever with the cam 89. The means for disengaging the latch 97 from the lug 96, and thus allowing the clutch operating wedge to be operated to engage the clutch, comprises a lever 98 provided at its lower end with a yoke, the arms

of which are pivotally mounted on the shaft 94 on opposite sides of the collar 95 and brake lever. One arm of the yoke is provided with a cam 99 arranged to engage a pin 100 on the pawl 97, and to force the pawl back out of engagement with the lug 96. The lever 98 is also provided with a depending arm 101 which is connected by means of a spring 102 with the brake lever 90 in such manner that the spring tends to swing the brake lever away from the cam 89. Such movement of the brake lever is prevented by the engagement of the pawl 97 with the lug 96 when the parts are in the position of Fig. 15. The lever 98 is also provided with a rod 103 extending across from one arm of the yoke to the other, and arranged to engage a lug 104 projecting up from the hub of the brake lever. The upper end of the lever 98 is connected by means of a link 105 with the end of an arm 106 of the lever 68 (Fig. 4). The link is provided with a yielding connection 107 of common construction.

25 When the treadle 79 is depressed to throw into operation the jack feeding pawls in the manner above described, the arm 106 of the lever 68 is moved in a direction to force the upper end of the lever 98 toward the left in Fig. 15. As the lever 98 is moved toward the left, the cam 99 acts against the pin on the pawl 97, as indicated in Figs. 16 and 17, and disengages the pawl from the lug 96. This releases the shaft 94, so that the clutch operating wedge is forced upward to engage the clutch members 80 and 81, thus throwing the mechanism which operates the compressing tools, and which operates the jack feeding pawl, into operation. The disengagement of the pawl 97 from the lug 96 also releases the brake lever 90, so that the brake is thrown away from the cam 89, and into the position indicated in Figs. 1 and 3. The jack is now intermittently advanced, and the compressing tools operated, until the leveling roll reaches the breast of the heel seat. The operator then throws into operation the mechanism for returning the jack, and in so doing he releases the lever 68, so that the pawl guard 67 is returned to normal position, throwing the jack operating pawls out of operation, and the lever 98 is moved toward the right. When the lever 98 is thus moved toward the right, the bar 103 acting on the lug 104 lifts the brake lever, until the brake shoe engages the periphery of the cam 89. Assuming that the brake shoe strikes the cam 89 on the part 108, the upward movement of the lever will be arrested before the pawl 97 has been raised far enough to engage the lug 96. Now as the cam 89 rotates, the brake shoe will ride over the shoulder 92 on the cam, as indicated in Fig. 12, and then as the brake shoe rides on to the low part 109 of the cam, the pawl 97 will be

raised, so that it will engage the lug 96 on the shaft 94, as indicated in Fig. 13. As the cam 89 continues to rotate, the brake shoe will ride over the rise 110 on the cam, and will be depressed. As the brake lever is moved downward by the cam at this time, the pawl 97 by its engagement with the lug 96 will throw the clutch operating wedge downward, thus disengaging the clutch members 80 and 81. The momentum of the parts will carry the cam 89 into the position indicated in Fig. 15, when the brake shoe acting against the shoulder 92 will bring the clutch member 80 and eccentric 35 to rest, with the compressing tools in their upper position.

The mechanism through which the operator reverses the movement of the jack, and throws the operating mechanism for the compressing tools and the intermittent jack feeding mechanism out of operation, comprises a lever 111 which is connected by means of a link 112 with a frame 113 pivotally mounted on drive shaft 114. The frame 113 carries two shafts 115 and 116 driven in opposite directions from the shaft 114 through a belt 117 which passes over pulleys on said shafts, and over an idler pulley 118 mounted on the frame 113. The two shafts 115 and 116 are provided with friction pulleys 119 and 120 arranged to be moved into and out of engagement with a friction drum 121 by the movements imparted to the frame 113 through the lever 111. The friction drum 121 is secured on a shaft 122 which carries the pinion 123 arranged to engage a segmental gear 124 secured to the crank shaft 6. The frame 113 is held normally in position with both friction pulleys 119 and 120 out of engagement with the drum 121, by springs 125 mounted on a rod 126 which is pivoted to the frame 113, the springs being arranged on opposite sides of a fixed lug 127, and engaging nuts threaded on the rod. The lever 111 is connected by means of a link 128 with a cam slide 129 mounted in the lever 68, and arranged to engage the latch rod 72 and disengage it from the lever when the operator moves the reversing lever 111 to reverse the movement of the jack.

When the operation of the compressing tools is to be arrested, and the movement of the jack reversed, the operator moves the lever 111 toward the right in Fig. 1, thereby operating the cam slide 129 to disengage the latch bar 72 from the lever 68, so that the lever 68 is operated to throw out the jack operating pawls, and to throw out of operation the mechanism for operating the pawls and for operating the compressing tools. This movement of the lever 111 also brings the friction pulley 119 into engagement with the friction drum 121 so that the pulley and drum operate to impart a return movement to the jack. After the mechanism for inter-

mittently advancing the jack, and for operating the compressing tools, has been thrown out of operation by the movement of the lever 111, either continuous forward or backward movements may be imparted to the jack to move the sole back and forth under the leveling roll by manipulating the lever to bring either the friction pulley 119 or the friction pulley 120 into engagement with the drum 121. The operator may thus, through the lever 111 which controls the movements of the jack, and through the lever 48 which controls the lateral inclination of the leveling roll, cause the leveling roll to operate upon any portion of the sole after the compressing tools have been thrown out of operation, and may thus cause the sole to be operated upon by the roll to any desired extent. When the operator releases the treadle 79, the latch rod 72 will re-engage the lug 74 on the lever 68, so that when the lever 79 is again depressed, the mechanism for intermittently advancing the jack, and the mechanism for operating the compressing tools, will be thrown into operation.

In operating upon some styles of shoes it is not desirable to subject all parts of the center of the sole to repeated compressions, and means are therefore provided for arresting the action of the center compressing tool during the operation of the compressing tools upon the sole. As shown in Figs. 1, 2 and 3, this means comprises a stop bolt 130 arranged to be moved into and out of the path of a lug 131 on the center tool-carrying rod 23. The bolt 130 is yieldingly mounted in a slide 132 which is normally held in position to retract the bolt by a spring 133. When the operation of the center tool is to be arrested, the operator forces in the slide 132, bringing the bolt 130 into the path of the lug 131, so that the bolt prevents the downward movement of the center tool during the downward movement of the tool-carrying head. So long as the bolt is in advanced position, therefore, the action of the center tool will be arrested, while the side tools will continue to operate upon the sole. Whenever the bolt is returned to its normal position, the center tool, as well as the side tools, will operate upon the sole.

It is usually desirable that the center compressing tool be thrown out of operation when operating upon the shank of the sole, and its operation may therefore be conveniently controlled by providing means whereby its operation is automatically arrested when the operator varies the lateral inclination of the leveling roll for operation upon the shank of the sole.

In Figs. 19, 20, 21 and 22, I have shown the form of mechanism for thus automatically arresting the action of the center compressing tool which I prefer to use. It is also

desirable that the side compressing and laterally rubbing tools should exert a greater pressure upon the sole when operating upon the shank portion than when operating upon the forepart of the sole, and I have accordingly provided means for varying the pressure exerted by the said tools during their operation on the sole. The means which I prefer to employ for this purpose is also shown in Figs. 19 to 22. As shown in these views, the stop bolt 134 for arresting the downward movement of the rod 23 which carries the center tool is arranged to be moved into and out of the path of a lug 135 on the rear side of the rod. The bolt is yieldingly mounted in a slide 136 which is normally forced in a direction to withdraw the bolt from the path of the lug 135 by a spring 137. The rear end of the slide 136 is connected to toggle levers 138, one of which is pivoted to the slide and the other of which is connected to a fixed pivot 139 on the bed 7. The pivotal connection between the toggle levers is connected by a link 140 with the short arm of a bell crank lever 141, the other arm of which extends down outside of the bed 7. The lower end of the bell crank lever is provided with a roll 142 arranged to engage a cam groove 143 in the lever 144 through which the operator varies the lateral inclination of the leveling roll 21.

When the lever 144 is in mid-position and the leveling roll is properly inclined to act upon the forepart of the sole, the bolt 134 is in retracted position so that the center tool will be actuated to operate upon the sole. Whenever the lever 144 is moved in either direction to vary the lateral inclination of the roll 21 for operation upon the shank, the cam 143 will act upon the roll 142 to rock the lever 141 in a direction to straighten the toggle levers 138 and thus advance the bolt 134 into position to arrest the operation of the center tool. The pressure exerted by the side tools upon the sole is also controlled through the movements imparted to the bell crank lever 141 by the lever 144 in varying the lateral inclination of the leveling roll for operation upon the shank or forepart of the sole. The means for accomplishing this comprises a slide 145 mounted to move vertically in the tool-carrying head 22 and provided with laterally extending arms 146, the outer ends of which are slotted to embrace the tool-carrying rods 25 and 26 and overlie the springs 27 and 28. The slide 145 is connected by a link 147 with one arm of a bell crank lever 148 which is pivoted at 149 on the bed 7. The vertical arm of the bell crank lever 148 carries a pin 150 mounted to slide vertically in the lever and normally supported in retracted position by a spring 151. The lower end of the pin is arranged to cooperate with a recess formed in the upper side of a lug 130

152 which projects laterally from the vertical arm of the bell crank lever 30 through which the tool carrying head is reciprocated. The pin is held normally in retracted position by its spring so that it is out of engagement with the recess in the lug 152. The upper end of the pin carries a roll 153 arranged to be engaged by the rear end of the lever 154 which is connected by a link 155 with the bell crank lever 141. When the bell crank lever 141 is operated by the movement of the lever 144 to vary the lateral inclination of the leveling roll for operation on the shank of the sole, the lever 154 is depressed, thus forcing down the pin 150 so that it engages the recess in the lug 152 so that the vertical arm of the bell crank lever 148 is connected with the vertical arm of the bell crank lever 30. The relative lengths 20 of the arms of the bell crank levers 30 and 148 are such that when the tool-carrying head is moved downward by the movement of the bell crank lever 30 the slide 145 will be moved downward more rapidly, thus compressing the springs 27 and 28 and increasing the force with which the tools are pressed against the sole. When operating upon the forepart the bell crank lever 141 will hold the lever 154 in raised position, so 25 that the pin 150 will be out of engagement with the recess in the lug 152, and the bell crank lever 148 will move idly as the tool-carrying head is reciprocated.

In Figs. 23 to 26 a construction is shown 30 in which means is provided for smoothing and shaping the heel and heel seat during the leveling operation. As shown in these views, the devices for smoothing and shaping the heel and shaping the heel seat comprise a series of hammers arranged to operate on the heel of a shoe supported on the jack. This series of hammers comprises a hammer 156 arranged to operate upon the back of the heel, and two sets of hammers 40 arranged to act upon the opposite sides of the heel, each set comprising two hammers 157 and 158. The hammer 156 is pivotally supported upon a rod 159 mounted in the upper end of a lever 160 and held yieldingly in advanced position in the lever by a spring 45 161. The hammer is held yieldingly in position in the end of the rod 159 by a spring 162, and the pivot for the hammer is so arranged that the operating surface of the hammer will automatically accommodate itself to the curvature of the shoe in the direction of the movement of the hammer over the curvature of the heel. The lever 160 is pivotally mounted on the jack 1, and 50 is provided at its lower end with a roll arranged to engage a cam 163 by which the lever is given a rapid oscillatory movement. The hammer carrying rod 159 is so mounted in the end of the lever 160 that the hammer 55 is caused to strike a blow upon the back of

the heel close to the sole, and to then move vertically while pressed against the shoe. By this hammering and rubbing action the back of the heel and heel seat is shaped, and the back of the heel is smoothed and finished. 70

The side hammers 157 and 158 are pivotally supported on the ends of rods 164 and 165 mounted in the upper ends of two levers 166 and 167 arranged on opposite sides of the heel post 168 of the jack. The hammers are mounted in the ends of the hammer carrying rods in such manner that their working faces will automatically conform to the lateral and longitudinal curvature of the 75 sides of the heel as the hammers engage and move over the surface of the heel. The hammer carrying rods are held yieldingly in advanced position in the levers by springs 169, and the rods are so mounted in the levers that when the levers are given an oscillatory movement the hammers are caused to strike blows upon the sides of the heel close to the sole, and to then move vertically away from the heel seat while held in engagement with the heel. This hammering and rubbing action shapes the heel and heel seat and smooths and finishes the sides of the heel. 80

Vibratory movements are imparted to the 95 levers 166 and 167 to move the hammers toward and from the heel, and the levers are also given vibratory movements to vary the position of the hammers 157 and 158 longitudinally of the shoe, so that the entire surface of the heel will be engaged and operated upon. The lever 166 is pivotally supported at 170 so that its upper end may be moved toward and from the shoe supported on the jack, and may move laterally. 100 The lower end of the lever is provided with a roll 171 engaging a cam groove 172 formed in a cam drum 173, the cam groove being so formed that it imparts rapid oscillatory movements to the lever to move its upper end toward and from the heel of the shoe supported on the jack. The lower end of the lever 166 also carries rolls 174 arranged to engage cam surfaces 175 formed on the cam drum 173, and shaped to vibrate the upper end of the hammer carrying lever longitudinally of the shoe supported on the jack. 110 The cams are so shaped that the hammers will be shifted longitudinally of the heel of the shoe between successive blows, so that successive blows will be dealt at different points upon the heel, and thus the entire heel will be subjected to a hammering and rubbing action by the series of hammers. The lever 167 carrying the hammers 115 157 and 158 for acting upon the opposite sides of the heel is actuated in the same manner by cams similar to cams 172 and 175. 120

The cams for operating the hammers which shape and smooth the heel and heel 125

seat are secured upon a shaft 176 mounted in the jack 1, and driven through a belt 177 from the shaft 2 on which the jack is pivoted. The shaft 2 is driven from the shaft 122 by means of a belt 178 passing over pulleys secured to the shafts. Thus during the forward and backward movement of the jack, the cam shaft 176 is rotated to actuate the hammers so that the heel seat is shaped and the heel smoothed during the operation of the leveling devices upon the sole of the shoe supported on the jack.

Having set forth the nature and object of the invention, and specifically described a machine in which it may be embodied, what I claim is:—

1. A sole leveling machine, having, in combination, a shoe supporting jack and a leveling device relatively movable to transfer the point of operation of the leveling device over the sole of a shoe supported on the jack, and means for repeatedly actuating said device during a single transfer of the point of operation along the sole to compress the sole and to move laterally toward the edge of the sole during each compression.

2. A sole leveling machine, having, in combination, a shoe supporting jack and a leveling device relatively movable to transfer the point of operation of the tool over the sole of the shoe supported by the jack and means for repeatedly actuating the tool during a single transfer of the point of operation along the sole to compress the sole and to outwardly stretch the margin of the sole during each compression.

3. A sole leveling machine, having, in combination, a shoe supporting jack and a sole leveling tool relatively movable to transfer the point of operation of the tool over the sole of a shoe supported on the jack, said tool being mounted to allow its working face to conform to the lateral curvature of the sole, and means for repeatedly forcing the tool against the sole and relieving the pressure as the point of operation is transferred along the sole, substantially as described.

4. A sole leveling machine, having, in combination, a shoe supporting jack, sole compressing tools arranged to act upon the opposite sides of the bottom of the sole of a shoe supported on the jack, means for relatively actuating the jack and tools to repeatedly force the tools toward the sole and relieve the pressure, and means for relatively moving the jack and tools to transfer the point of operation along the sole, substantially as described.

5. A sole leveling machine, having, in combination, a shoe supporting jack, sole leveling tools arranged to act simultaneously upon the opposite sides of the bottom of the sole of a shoe supported on the jack, means for actuating the tools to compress the sole and to move laterally of the sole while in

engagement therewith, said tools being mounted to allow their working faces to conform to the lateral curvature of the sole, and means for relatively actuating the jack and tools to transfer the point of operation 70 along the sole, substantially as described.

6. A sole leveling machine, having, in combination, a shoe supporting jack, leveling tools arranged to act upon opposite sides of the bottom of the sole of a shoe 75 supported on the jack, means for repeatedly forcing said tools toward the sole and relieving the pressure as the points of operation are transferred along the sole, and means for independently determining the 80 force of compression on the opposite sides of the sole, substantially as described.

7. A sole leveling machine, having, in combination, a shoe supporting jack, leveling devices arranged to act upon opposite 85 sides of the bottom of the sole of a shoe supported on the jack, and means independent of the sole edge for actuating the leveling devices to move laterally outward toward the edges of the sole at the points of 90 operation while independently applying pressure to the opposite sides of the sole, substantially as described.

8. A sole leveling machine, having, in combination, a shoe supporting jack, leveling tools arranged to independently and simultaneously act upon the opposite sides and upon the center of the bottom of the sole of a shoe supported on the jack, and means for relatively actuating said tools and 100 jack to progressively and repeatedly force the tools toward the sole and relieve the pressure as the points of operation are transferred along the sole, substantially as described.

9. A sole leveling machine, having, in combination, a shoe supporting jack, leveling tools arranged to independently and simultaneously act upon the opposite sides and upon the center of the bottom of the 110 sole of a shoe supported on the jack, means for relatively actuating said tools and jack to progressively act upon the sole, and means for arresting the action upon the center of the sole during the operation of 115 the tools, substantially as described.

10. A sole leveling machine, having, in combination, a shoe supporting jack, leveling tools arranged to act upon the opposite sides of the bottom of the sole of a shoe 120 supported on the jack and mounted to allow their working faces to conform to the lateral curvature of the sole, a tool arranged to act upon the center portion of the sole mounted to allow its working face 125 to conform to the longitudinal curvature of the sole, and means for repeatedly forcing the tools against the sole, substantially as described.

11. A sole leveling machine, having, in 130

combination, a shoe supporting jack, leveling devices for subjecting the sole to repeated compressions perpendicular thereto during a single transfer of the points of 5 operation along the sole, a leveling device arranged to simultaneously operate upon a different portion of the sole to smooth out the sole, and means for relatively actuating the jack and leveling devices to transfer 10 the points of operation of the leveling devices along the same portions of the sole, substantially as described.

12. A sole leveling machine, having, in combination, a shoe supporting jack, a vertically reciprocating leveling tool arranged to act upon the margin of the sole of a shoe supported on the jack, and means for reciprocating the tool during the transfer of its point of operation along the sole and 20 for moving it outward toward the edge of the sole while pressed against the sole, substantially as described.

13. A sole leveling machine, having, in combination, a shoe supporting jack, a leveling tool arranged to act upon the margin of the sole of a shoe supported on the jack, a vertically reciprocating head in which the tool is mounted, a spring between the tool and head, and means for reciprocating the 30 head during the transfer of the point of operation of the tool along the shoe sole and for moving the tool outward toward the edge of the sole while pressed against the sole, substantially as described.

14. A sole leveling machine, having, in combination, a shoe supporting jack, and means for subjecting the sole to repeated compressions perpendicular thereto during a single traverse of said means along the 40 sole, applying an outward stretching pressure to the margin of the sole, and applying a longitudinally progressive pressure to the sole, substantially as described.

15. A sole leveling machine, having, in combination, a shoe supporting jack, means for subjecting the sole to repeated compressions during a single traverse of said means along the sole, and simultaneously acting means for applying a longitudinally progressive pressure to the sole after it has 50 been subjected to repeated compressions, substantially as described.

16. A sole leveling machine, having, in combination, a shoe supporting jack, means for repeatedly applying a laterally progressive pressure upon the side of the bottom of the sole of a shoe supported on the jack during a single traverse of said means along the sole, and means for applying a subsequent 60 longitudinally progressive pressure to the same portions of the sole, substantially as described.

17. A sole leveling machine, having, in combination, a shoe supporting jack, a level-

ing roll, means for relatively actuating the 65 roll and jack, to transfer the point of operation along the sole and to vary the lateral inclination of the roll, means for repeatedly compressing the sole, and means for arresting the operation of the compressing means 70 during the operation of the roll, substantially as described.

18. A sole leveling machine, having, in combination, a shoe supporting jack, a leveling roll relatively movable to transfer the 75 point of operation along the sole, and means for tilting the roll to vary its lateral inclination by laterally shifting the axis about which it is tilted, substantially as described.

19. A sole leveling machine, having, in combination, a shoe supporting jack, a leveling roll, a laterally movable carriage in which the roll is mounted, means for shifting the carriage and means for tilting the roll in the carriage by the lateral shifting 85 of the carriage, substantially as described.

20. A sole leveling machine, having, in combination, a shoe supporting jack, a leveling roll, and mechanism for varying the lateral inclination of the roll including locking 90 gearing for locking the roll against displacement under the pressure exerted thereon by the sole, substantially as described.

21. A sole leveling machine, having, in combination, a shoe supporting jack, a leveling roll, and an operating lever and connecting means between the lever and roll for varying the lateral inclination of the roll by movement of the lever, including means for locking the roll against displacement 100 under the pressure exerted thereon by the sole, substantially as described.

22. A sole leveling machine, having, in combination, a shoe supporting jack, a leveling roll, means for varying the lateral inclination of the roll to operate upon the shank or forepart of a sole, means for repeatedly compressing the sole, and means for varying the force of the compression in varying the lateral inclination of the roll, 110 substantially as described.

23. A sole leveling machine, having, in combination, a shoe supporting jack, a leveling roll, means for varying the lateral inclination of the roll for operating on the 115 shank or forepart of a sole, means for repeatedly compressing the sole, and means for controlling the operation of the compressing means in varying the lateral inclination of the roll, substantially as described.

24. A sole leveling machine, having, in combination, a shoe supporting jack, a leveling roll, means for varying the lateral inclination of the roll for operating on the 125 shank or forepart of the sole, means for repeatedly compressing the sole, and means for arresting the action of the compressing

means in varying the lateral inclination of the roll for operation upon the shank, substantially as described.

25. A sole leveling machine, having, in combination, a shoe supporting jack and sole leveling means relatively movable to transfer the point of operation along the sole of a shoe supported on the jack, and means for operating upon the heel of the shoe supported on the jack during the leveling operation, substantially as described.

26. A sole leveling machine, having, in combination, a shoe supporting jack and sole leveling means relatively movable to transfer the point of operation along the sole of a shoe supported on the jack, and means for shaping the heel seat and smoothing the heel of a shoe supported on the jack during the leveling operation, substantially as described.

27. A sole leveling machine, having, in combination, sole leveling means, a shoe supporting jack, means for moving the jack to transfer the point of operation of the

leveling devices along the sole of a shoe 25 supported on the jack, means mounted upon the jack for operating upon the heel of the shoe supported on the jack, and mechanism for actuating said means during the movements of the jack, substantially as described. 30

28. A sole leveling machine, having, in combination, sole leveling means, a shoe supporting jack, means for moving the jack to transfer the point of operation of the leveling means along the sole of a shoe supported 35 on the jack, a series of hammers mounted upon the jack and arranged to operate upon the heel of a shoe supported on the jack, and means for actuating said hammers during the movement of the jack, substantially 40 as described.

In testimony whereof I affix my signature, in presence of two witnesses.

EUCLID I. LA CHAPELLE.
